UNITED STATES PATENT OFFICE.

ARTHUR P. SCOTT, OF CHICAGO, ILLINOIS, ASSIGNOR TO CHILE EXPLORATION COMPANY, OF NEW YORK, N. Y., A CORPORATION OF NEW JERSEY.

ELECTRIC FURNACE AND METHOD OF PRODUCING MOLTEN MAGNETITE THEREIN.

1,226,122.

Specification of Letters Patent.

Patented May 15, 1917.

Application filed November 17, 1915. Serial No. 61,905.

To all whom it may concern:

Be it known that I, ARTHUR P. SCOTT, a subject of the King of Great Britain, residing at Chicago, county of Cook, and State of Illinois, have invented certain new and useful Improvements in Electric Furnaces and Methods of Producing Molten Magnetite Therein; and I do hereby declare the following to be a full, clear, and exact description of the invention, such as will enable others skilled in the art to which it appertains to make and use the same.

This invention relates to improvements in single phase alternating current electric furnaces of the direct arc type, and particularly to furnaces for the melting of iron ore and the production of molten magnetite therefrom; and to methods of producing a protective layer of magnetite, and molten magnetite, therein.

In furnaces of this type, when utilized for melting ore, (purple ore or leached Rio Tinto cinder), it has been found that the arc tends to melt principally downward and with very little lateral fusion, and that the bath thus tends to assume the form of a deep well of small cross section instead of the usual shallow basin. In order to protect the bottom contact from overheating and injury during this melting process, the furnace bottom is provided, according to the present invention, with a protective layer of solid magnetite above the bottom contact. While the ore itself is a non-conductor, it becomes a good conductor when molten and cast, so that the protective layer itself forms the bottom electrode.

A furnace embodying the invention and illustrative thereof is shown in the accompanying drawings in central vertical section.

The furnace illustrated is of the tilting type and is provided with suitable means (not shown) for rocking or tilting it into the position shown in dotted lines. The furnace is constructed of appropriate refractory material 1 within an outer casing and is provided with a top 2, and bottom

rocker supports 3 mounted upon the foundation 4.

The upper graphite electrode is indicated at 5, carried by an arm 6. This arm is adjustable in the vertical support 7 by means of suitable adjusting or operating mechanism 8. The bottom contact is indicated at 10 and the lateral opening in the furnace, by means of which access may be had thereto, at 11.

Above the bottom steel contact, and forming a bottom protective layer, is the cast layer of magnetite 9.

In the production of molten magnetite it is essential that the furnace lining be of a basic nature. In practice this lining is made of magnesite. A mixture of the magnesite with pitch is tamped into the shell around a wooden form. After removing the form, the pitch is removed, as by a slow coke fire, and the furnace is ready for operation.

In starting the furnace and producing the layer of magnetite, the ore (e. g. purple ore or leached Rio Tinto cinder) in suitable amount is piled up around the sides of the hearth to allow the upper graphite electrode to pass through and make contact with the bottom steel electrode. This is necessary because of the non-conducting character of the raw ore. After the electric current has been turned on, the upper graphite electrode is lowered into contact with the bottom to make the arc and then gradually raised.

As fast as the material below the arc is melted, fresh ore is rabbled down from the sides with a wooden pole to prevent the bottom contact from being eaten away by the molten magnetite. As soon as a sufficient quantity of pasty material has accumulated below the arc (e. g. about half an hour), the rabbling is stopped and the current left on for five or ten minutes to allow the melt to become fluid and clear. The current is then cut off and the furnace allowed to cool for a suitable period of time (e. g. three or four hours) to permit the bottom to set. The operation is repeated until the magnetite bot-

tom has attained a sufficient thickness for use in the normal melting operation, and the furnace is then allowed to remain inactive for a further period of time, say over 5 night.

Because of the tendency of the arc to melt principally downward, and with little lateral fusion, and of the resulting tendency of the bath to assume the form of a deep well 10 of small cross section instead of the usual shallow basin, it has been found that the magnetite bottom immediately below the electrode was frequently penetrated, making it necessary to suspend operations or 15 even to build up an entire new bottom.

It has been found, however, that this difficulty can be readily overcome by the addition of broken magnetite electrode scrap. This scrap, when added to the bath, is but 20 slowly absorbed, the raw ore going into solution, or becoming molten, much more readily. This scrap settles to the bottom of the bath, and where raw ore is added from time to time remains practically unattacked.

25 Accordingly, when the magnetite bottom has become penetrated and needs repairing, or to prevent danger of such penetration, the magnetite scrap is added. It may thus form a layer at the bottom of the molten 30 ore and above the protective layer of magnetite, or it may be or become incorporated in this protective layer itself.

The roof of the furnace can be made of basic material, or even of silica brick, the 35 silica remaining practically unaffected. It tends to slag with the ore when the latter is accidentally brought into contact with it, but as this can readily be avoided the tendency is negligible.

40 After the protective layer of magnetite has been formed, the furnace is ready for use in the normal operation of melting the ore for the production of magnetite suitable for casting purposes, *e. g.* for casting 45 electrodes.

In the normal melting operation, the graphite electrode is first lowered into contact with the magnetite bottom, a suitable 50 charge of the ore is thrown in around the electrode, and the electrode gradually raised as fast as the ore near the arc is melted and becomes conducting. At the same time the outlying portions of the charge around the periphery of the hearth are gradually poled 55 down into the zone of fusion. When the bath has become clear and fluid and of a proper temperature, it is ready for pouring.

Before pouring, and after the clear fluid 60 bath of sufficient quantity has accumulated, it is in practice advantageous to add a further small portion of the ore and to pour the molten ore as soon as this added portion has been absorbed. This final addition serves both as a temperature check and to 65 limit the formation of an excess of ferrous

oxid. The temperature of the ore when cast is about 1590° C.

The method of casting the electrodes after a suitable bath has been produced forms the subject-matter of a companion application, Serial No. 61,904, filed November 17, 1915.

From the above description it will be seen that the magnetite bottom not only protects the magnesite lining from the direct 75 heat of the arc, but it takes the place of the steel bottom contact preventing excessive corrosion at this point and itself forming the lower electrode. It will further be seen that by the simple expedient of adding cast 80 magnetite electrode scrap to the bath, or incorporating it in the bottom protective layer, the magnetite layer is itself preserved and protected from overheating and penetration.

85 What I claim is:

1. An electric furnace of the direct arc type provided with a bottom protective conducting layer of magnetite; substantially as described.

90 2. An electric furnace of the direct arc type provided with a lower fixed contact and an upper movable electrode, and with a protective conducting layer of magnetite overlying said bottom contact and forming 95 the bottom electrode; substantially as described.

3. An electric furnace of the direct arc type provided with a bottom protective conducting layer of magnetite with which cast 100 magnetite scrap is incorporated; substantially as described.

4. An electric furnace of the direct arc type provided with a lower fixed contact and an upper movable electrode, and with a 105 protective conducting layer of magnetite overlying said bottom contact and forming the bottom electrode, said layer of magnetite having cast magnetite scrap incorporated therewith; substantially as described. 110

5. A single phase alternating current electric furnace of the direct arc type provided with a lower fixed electrode and an upper movable electrode, and with a protective conducting layer of magnetite overlying 115 said bottom contact and forming the bottom electrode; substantially as described.

6. In a method of producing molten magnetite, melting the ore between the upper and lower electrodes of an electric arc furnace to produce a body of molten ore, and allowing said body of ore to set to form a bottom conducting layer of magnetite above the lower electrode; substantially as described.

120 7. The method of producing molten magnetite, which comprises melting the ore between the upper and lower electrodes of an electric arc furnace to produce a fluid body of the magnetite, allowing said body to set to form a bottom protective layer, and pro- 125

130

tecting the bottom contact by such protective layer during the subsequent melting of further portions of ore; substantially as described.

5. In a method of producing molten magnetite, melting the ore between the upper and lower electrodes of an electric arc furnace to produce a fluid body of magnetite, allowing such body to set, and melting fur-

ther amount of ore above said protective layer of magnetite to produce further amounts of fluid magnetite, and permitting said further amounts of magnetite to set to form a bottom protective layer of suitable thickness; substantially as described.

In testimony whereof I affix my signature.

ARTHUR P. SCOTT.
